Primary Examiner — Lilyana Bekic*(74) Attorney, Agent, or Firm* — Knobbe Martens Olson & Bear, LLP(57) **CLAIM**

The ornamental design for a medical fluid transfer system, as shown and described.

DESCRIPTION

FIG. 1 is a front perspective view of a medical fluid transfer system with various features shown in broken lines;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the figures depict portions of the medical fluid transfer system that form no part of the presently claimed design.
